UNITED STATES PATENT OFFICE.

MARK GLOVER MALPAS, OF MORRISVILLE, PENNSYLVANIA.

PROCESS FOR EMBOSSED PORCELAIN, STONE, AND LIKE MATERIAL.

1,209,183.

Specification of Letters Patent. Patented Dec. 19, 1916.

Application filed June 19, 1915. Serial No. 35,143.

To all whom it may concern:

Be it known that I, MARK GLOVER MALPAS, a citizen of the United States, and a resident of Morrisville, in the county of Bucks and State of Pennsylvania, have invented a certain new and useful Process for Embossing Porcelain, Stone, and like Material, of which the following is a full, clear, and exact specification.

10 This invention relates to a class of processes for producing embossed designs on porcelain, stone, and like material.

My invention has for its object primarily to provide a process designed to be employed 15 for facilitating the work of producing designs, figures, and characters in relief on the surface of porcelain, stone, and like material whereby signs, inscriptions, name-plates, and similar classes of art may be carved 20 without requiring the employment of skilled workmanship as is incident to the methods ordinarily in use. This is accomplished by the process which consists mainly of removably applying one, or more pattern 25 members of the characters, or designs of the subject matter to be produced to the surface of the material which is to be carved, and then forcing under air-pressure particles of a cutting substance in contact with 30 the material so that the material surrounding the pattern will be cutaway, the said pattern member being resistible to the cutting action of the substance.

A further object of the invention is to 35 provide a process which is susceptible of producing in a simple manner novel and striking embossed color-effects especially on porcelain.

A practical embodiment of the invention 40 is represented in the accompanying drawing forming a part of this specification in which similar characters of reference indicate corresponding parts in all the views, the said invention being more fully described hereinafter, and then pointed out in the claim at the end of the description.

In the drawing, Figure 1 is a perspective view of a block, or plate, or body of porcelain, or stone, or like material adapted to 45 be embossed by the employment of my process. Fig. 2 is a view of the block of the material showing a pattern member removably applied thereon as well as showing one form of means for carving the block by the use of particles of a cutting substance forced thereagainst under air-pressure. Fig. 3 is a

perspective view of the block when embossed. Fig. 4 is a perspective view of one of the pattern members. Fig. 5 is a perspective view of a form of block adapted 60 to be embossed, and having a colored layer thereon. Fig. 6 is a view of the block shown in Fig. 5 when undergoing the process of being embossed. Fig. 7 is a perspective view of the block when embossed, and Fig. 65 8 is a view showing a number of the pattern members representing letters.

The process constituting my invention is carried into practice by providing one, or a suitable number of pattern members, as 70 10, which may represent a figure or design, as shown in Fig. 4, or the pattern members may represent one, or a number of letters, or other characters, as illustrated in Fig. 8. These pattern members may be made of any 75 desired material adapted to resist the cutting action of particles, or granules of sand, or pure silica, or fluorspar, or other substance of sufficient hardness to cut stone, porcelain, and similar material when forced 80 thereagainst under pressure, though I prefer to form the pattern members 10 of rubber which is especially adaptable for resisting the action of the cutting material owing to its resilient properties, it having been 85 discovered that pattern members of rubber tend to withstand so efficiently the action of the cutting material that practically no wear is apparent even following repeated uses thereof.

To prepare a block, or slab, or plate, or body of stone, or porcelain, or other material, as 11, for being embossed, one, or more of the pattern members 10 are disposed in a desired arrangement on the surface of the 95 block, and the pattern members are caused to be removably adhered thereto by the use of any adhesive substance, such as glue, paste, and the like. A suitable portion of the block surrounding the pattern members is 100 then subjected to the action of particles, or granules of sand, or pure silica, or fluorspar, or other substance, as 12, of sufficient hardness to freely cut the block, and this cutting substance is forced against the surface of the 105 block under air-pressure, or by any other force through the employment of any well-known, or preferred type of pneumatic blowing apparatus, as 13, or other means. As the pattern members will serve to resist the action of the cutting substance the portions of 110 the block covered by the members will not

be affected by the cutting substance, and when the other portion of the block has been cut to a suitable depth so that the design, or figure, or character extends sufficiently in relief the pattern members are removed therefrom. In turn the design, or character will appear in accurately carved embossed form.

As illustrated in Figs. 5, 6, 7, my process 10 may be advantageously employed to produce very durable, novel, and attractive signs, name-plates, etc., in color-combinations by embossing blocks, plates, or slabs especially of porcelain. This is accomplished by providing commonly known forms of blocks, 15 or plates of porcelain made with a number of layers of different colors, such as white and blue, as 14 and 15. One, or a number of the pattern members 10 are suitably arranged on the exposed surface of the colored layer 15, or vice versa, as illustrated in Fig. 6, the pattern members being removably cemented thereon by the use of any adhesive substance. The part of the block, 20 or plate of the porcelain surrounding the pattern members is then cut away by means of the cutting substance being blown thereagainst by pneumatic pressure, as hereinbefore explained, and if desired a portion, or 25 the entire layer, except the parts thereof which are covered by the pattern members, may be cut away. In this manner the embossed characters, or designs may be produced so as to appear in striking contrasted 30 color-effects on the body proper of the porcelain. Moreover, by the use of this process the work of embossing designs and charac-

ters on stone, or porcelain, and like material may be effectually accomplished with unusual facility, and without requiring a high 40 order of skilled workmanship to be employed.

In the foregoing description, I have embodied the preferred form of my invention, but I do not wish to be understood as limiting myself thereto, as I am aware that modifications may be made therein without departing from the principle, or sacrificing any 45 of the advantages of this invention, therefore I reserve to myself the right to make 50 such changes as fairly fall within the scope thereof.

Having thus described my invention, I claim as new and desire to secure by Letters Patent:—

A process for producing two-color embossed stone or the like, consisting of taking two layers of different colored material, uniting them to form one block, applying a resilient pattern to the top layer corresponding 60 to the character or design desired to be produced, forcing under pressure particles of a cutting substance into contact with the material surrounding the pattern so that said material will be cut away, and continuing 65 said cutting until the second layer has been exposed.

This specification signed and witnessed this fourteenth day of June, A. D. 1915.

MARK GLOVER MALPAS.
